DUMP-CAR.

1,000,175.

Specification of Letters Patent. Patented Aug. 8, 1911.

Application filed December 22, 1906. Serial No. 349,104.

To all whom it may concern:

Be it known that I, FRANK S. INGOLDSBY, residing at St. Louis and State of Missouri, have invented a certain new and useful Improvement in Dump-Cars, of which the following is a full, clear, and exact description, reference being had to the accompanying drawings.

This invention relates to dump cars wherein there are dumping doors forming a portion of the bottom of the car.

The object of the invention is threefold: first, to provide dumping doors and stationary members in such form that when the doors are closed the bottom of the car shall be substantially flat throughout its extent, while when the doors are dropped there shall be no flat surfaces whatever on which material might lodge. The second feature involved is the arrangement of longitudinal and cross beams so that the longitudinal beam carries an arbitrary portion of the load, and any excess of load above this arbitrary amount is carried by the cross beams to the side girders of the car. Third, my invention includes a new, simple, and effective mechanism for raising the dumping doors.

In the drawings, Figure 1 is a side elevation of my car; Fig. 2 is a plan thereof; Fig. 3 is a vertical cross section; Fig. 4 is a partial longitudinal section, as indicated by the line 4-4 on Fig. 3; Fig. 5 is a perspective of the parts providing the longitudinal crown; Fig. 6 is a perspective of the corner of the car, illustrating the method of operating the door raising mechanism; Fig. 7 is a side elevation of the head to which the door raising cables are attached; Fig. 8 is an edge view of such head; Fig. 9 is a cross section through one of the cross beams of the car, this section being in a plane parallel with Fig. 1; Fig. 10 is a view illustrating in cross section a modified form of longitudinal sill member; Figs. 11 to 14 inclusive illustrate modifications of the cross members—Fig. 11 showing the cross member as made in one piece, Fig. 12 showing it as a rolled beam carried by channels, Fig. 13 as a casting to which are riveted vertical plates, and Fig. 14 as a built-up structure.

The means for maintaining the dumping

doors in their elevated position is omitted from the illustrations for purposes of clearness. It will be understood that any suitable means may be employed, as for instance the usual Ingoldsby method of projecting floor beams and cooperative hooks on the car side, such means being illustrated for example in my Patent No. 744,201.

The car shown herein is of what is known as the Ingoldsby type, that is, it has a central longitudinal beam to which are hinged dumping doors, which extend when closed to the sides of the car and are adapted to swing downward at their outer edges to discharge the load outwardly. The present invention provides such car in a form wherein the entire bottom surface of the car is substantially flat and on the same level when the doors are closed, but becomes a series of inclined shedding surfaces throughout when the doors are dropped. I accomplish this by providing shedding crowns, both longitudinal and transverse, and arranging the doors so that when closed their upper surfaces are substantially flush with the upper surfaces of the crowns. These crowns therefore do not interfere when the doors are closed with the level floor of the car, while when the doors are dropped they prevent lodgment of material.

As shown, the car has girder sides 15, ends 16, and a longitudinal center sill or sills 17, longitudinal alined crowns, as 18, carried thereby, cross beams 20, connecting the longitudinal sill with the car sides, these cross beams having shedding crowns 21. The car sides are shown with vertical reinforcing members 23, extending below the sides and connected with the cross beams 20.

25 represents the dumping doors, which are hinged to the central longitudinal structure.

As shown in Fig. 3, the central longitudinal structure is in the nature of a pair of sills, or a box girder, comprising the longitudinal channel beams 30, the bottom plate 31, and the top plates 32. Surmounting this top plate is the structure illustrated in Fig. 5. This comprises a pair of plates 34, riveted to the upper flanges of the channels 30 through the plate 32, these plates 34, inclining and coming together and continuing

vertically as at 35 for a suitable distance, and then turning outward horizontally as at 36. Above the horizontal portions 36 is a plate 37, which is surmounted by filling blocks 38 (Fig. 3), while above this filling block is the arc-shaped plate or crown 18. Rivets 40 pass through this crown, the filling block, the plate and the flanges 36, binding the structure together and making it a substantial compression member, thus giving added depth and strength to the box girder.

Secured to the outer side of one of the vertical plates 35, and extending through openings in these plates, is a casting 42, which is flanged so as to come beneath the flange 36, and is riveted in place to the flange 36 and the vertical portions 35. This casting carries a pair of vertical cross webs 44. The dumping doors 25 have floor beams 45 on their under sides, which extend inwardly to the centers of the car. Floor beams from opposite sides come between the webs 44, and are hinged at the longitudinal center of the car by the hinge pin 46 extending through alined holes in such webs. This provides a simple and effective method of hinging the dumping doors.

Now the shedding crown 18 is formed in the arc of a circle whose center is the axis of the hinge pin 46. The doors are provided at their inner edges with inwardly extending shields 47, consisting of plates, the free ends of which are adapted to rest on and engage the curved crown 18. These plates may be tapered on their under sides to make a closer fit if desired. The effect of this structure is that when the doors are closed the inner edges of the shields are close to each other, and what space there is between them is occupied by the shedding crown, which for such short distance may be considered as substantially flat, whereby, the doors when closed present a substantially flat surface from one side of the car to the other. When the doors are dropped, however, the shields slide down on the shedding crown while maintaining their contact therewith, so that when in discharging position there is a continuous inclined surface from the apex of the crown to the outer edge of the doors, whereby there is no space for lodgment of material.

To prevent leakage of material under the ends of the shields 47, I provide at the ends of such shields filler castings 49, which are curved on their under edges to make a close engagement with the crown 18, and have vertical ends making a close connection with the cross beams with which the edges of the door coöperate.

If desired, in place of the built-up longitudinal box-girder beam as shown, there may be employed, for example, a single longitudinal member which acts both as the sill and

the shedding crown. This is illustrated in Fig. 10, where such member is shown at 50 and is in the nature of an I-beam having an arc-shaped upper edge, as shown at 51. The dumping door 25, has its floor beam 45, hinged in the plane of the vertical web of the I-beam between ears 52, carried by such beam. The axis of this hinge is the center of the arc 51. The floor beam carries the shield 47, as before, which engages such arc.

As stated, the cross beams of the car carry shedding crowns. As shown in Figs. 3 and 4, the cross beams are made of a pair of channels 20, surmounted by a plate 55, on which is mounted the crown 21, there being suitable filling blocks 57, between the crown and the plate 55. The filling block is shown in Fig. 9 and also in Fig. 3, where the member 21 is broken away. Suitable rivets 58, extend as shown through the crown, the filling block, the plate and the flanges of the channels. The highest points of crowns 21 are substantially on a line with the top surface of the dumping doors, wherefore these crowns preserve a substantially level floor when the doors are closed. The small amount of space between the apex of the crowns and the ends of the doors is immaterial. Inasmuch as the various stationary members of the floor do not rise higher than the tops of the doors, the floor may be loaded with any material which can be carried on the level floor of an ordinary car.

Depending from the cross beams are suitable sector-shaped shields 56, which are adapted to coöperate with the ends of the dropped doors to make discharging chutes.

To securely connect the cross bars with the longitudinal structure, forming a cross truss to allow the excess of loading to be carried to the car sides, I provide the channel ties 60, which extend across the car as tension members. These channels have their flanges downward and bend diagonally, passing beneath the central longitudinal sill structure. As shown in Figs. 3 and 4, this tension channel extends between the members 20 and has its flanges riveted to the webs of these members. The space between the tension channel 60 and the outer sides of the longitudinal sill structure may be occupied by vertical plates 61, which are flanged and riveted to the various members mentioned. The outer ends of the tie channels extend upward beyond ends of the cross beams 20 and are securely fastened to the sides of the car.

The described arrangement of channels passing across the upper side of the longitudinal beam and across its lower side makes a very rigid truss, the longitudinal beam acting as the strut therefor. This cross bearer is adapted to have its members either in tension or compression, according to the design of the car, and according to whether

used as bolsters or between the same. I arrange the longitudinal sill members so that they pass from one bolster to the other; or, as shown, from one end of the car to the other,—the longitudinal members and the cross structures intersecting each other. Wherefore, the longitudinal structure in addition to taking care of the buffing and jutting, carries such arbitrary portion of the load as is desired, while all excess of the load is carried by the cross structure to the car sides. This method of designing a car allows longitudinal members to be made very light and enables a saving in material. The cross members instead of being built up may be each a continuous single member in the nature of an I-beam, as shown in Fig. 11, wherein 63 represents such member. In Fig. 12, the cross member is shown at 64 as a rolled beam extending crosswise of the car and riveted directly to the flanges of the channel beams 20. In Fig. 13, the cross structure is a continuous casting 65, which has depending flanges 66, to which are riveted vertical plates 67, taking the place of the channels. In Fig. 14 the crown 21 is riveted through the filling member 57 to the channel 68 which has its flanges riveted to the vertical plates 20. In this view the crown 21 overhangs the plates 20 at an angle and thus provides cutting edges 72 with sloping sides, whereby any material on the shield plates 69 (hereinafter described) will be easily cut through, enabling a very tight joint.

The various forms of cross beams and longitudinal beams shown are not to be taken as an enumeration of all forms, but simply as an illustration of the fact that various forms may be employed and still have the essential characteristics of my invention.

To prevent leakage of fine material, I provide shield-strips extending in the form of flanges from the lower edges of the doors. These strips are shown, in Figs. 4, 9 and 12, at 69 as flat plates secured to the under side of the door near its end and projecting beyond such end to engage the under side of the cross beam. In Fig. 11 the shield is shown at 70 as secured across the end of the door, extending on to the upper side thereof, and having the flange 71, adapted to extend below the cross beam. In Fig. 3, shield plates 73 are shown carried by the projecting portions of the floor beams 45, these plates being adapted to abut the under side of the car side. As shown, this car side has on its lower edge an inner tension or reinforcing plate 74, and an outer angle 75, which parts act as the lower cord of the girder constituting the side.

As hereinbefore stated, the mechanism for holding the doors in their closed position is not shown. There is shown in Figs. 1, 3, 6, 7 and 8, a very simple and efficient

mechanism for raising the doors to their closed position, after which they may be locked by any suitable means. This raising mechanism consists of a series of cables 80, the lower ends of which are connected to brackets 81, secured to the under sides of the doors, and the upper ends of which are secured to a traveling cross head 82, movably carried on the upper part of the car. As shown, this cross head is on the end of the car, the cables passing from the cross head around guide sheaves 83 at the corners of the car, and over pulleys 84, carried at the sides. These pulleys 84, are held between the car side and straps 85 secured to the side. The pulleys lie between the adjacent vertical reinforcing members 23, as shown, these members acting as a guard for the vertical portion of the cables.

As shown in the drawing, the raising mechanism is divided, the transversely divided halves of the car being operated from corresponding ends. The brackets 81, at the ends and mid point of the car are secured to only one door, as shown, while intermediate the brackets are in the form of straps secured to consecutive doors. By securing the same brackets to two doors the number of cables is reduced. As shown, four cables only are required to raise three doors.

The cables, rising from the brackets, first pass over suitable guide sheaves 86. The corner cable rises thence directly over the guide sheave 87, while the other cables pass upwardly around the pulleys and corner sheaves mentioned, these cables lying close to the side of the car and extending through openings 88, in the vertical angle members 23.

As shown, the cables for one side of one half of the car all come into the same cross head 82, which is provided by a pair of vertical plates. These plates carry projecting rollers 89, and are guided by cleats 90, secured to the end of the car. Secured to the cross head is a cable 91, which extends around a winding shaft 92. The cables 91, from opposite cross heads are shown as secured to the same shaft, wherefore the rotation of this shaft is adapted to elevate the doors on both sides of that half of the car. To rotate the winding shaft, I have shown it as provided with a gear 93, which is adapted to be rotated by hand crank 96, a suitable ratchet and pawl 97, being adapted to hold gain made in winding.

Any suitable mechanism may be employed to disconnect the crank from the winding shaft when the doors are dropped, to prevent the crank being thrown around violently and thereby possibly causing injury. This mechanism may be, for example, similar to that shown in my Patent No. 682,660, wherein it is automatically disconnected from the releasing mechanism for

5 the doors. For the purpose of illustration I have shown this engagement as being effected by sliding the pinion 94 on its shaft out of engagement with the gear 93. This 6 sliding may be accomplished by having the pinion splined on the shaft and shiftable by a suitable shifter lever 98.

While the raising mechanism as shown herein is arranged so that the doors may be 10 raised half from one end of the car and half from the other, it will of course be understood that they may be all raised from one end, if desired, the cables being all carried to that end. Similarly, in place of 15 having one winding shaft at the end which operates both sides of the car, there may, if desired, be two winding shafts, so that each side may be raised independently, and each of such shafts may operate half or a quarter of the car, thus reducing the power required. I have shown the cables for raising the doors as located on the outer side of the car. Such is the preferable arrangement for a gondola car, as illustrated in the 20 drawing. In the case of a box car, however, the cables and sheaves are preferably located inside of the car, or between the outer and inner sheeting of the car side. These, and many other adaptations, are so 25 well understood as not to require further illustration or explanation.

It will be seen from the above description that I have provided a car in which, when the doors are closed, there is a substantially 30 flat bottom throughout the car, wherefore the car may be used for loading any material adapted to be carried by such flat bottom. If such material is dumpable, the entire load will be discharged from the dumping doors, there being no horizontal surfaces on which it may lodge. If the material is fine, for example wheat, it still cannot be lost by leakage, owing to the close 35 contact which the shields on the doors make with their cooperating members. My car is thus adapted for a great variety of uses.

I claim:

1. In a dump car, the combination of a stationary member having a curved upper 40 surface, a hinged dumping door, and a shield carried by said door and adapted to engage said surface as the door drops.

2. In a dump car, the combination of a longitudinal structure having a shedding 45 surface, dumping doors hinged thereto and having their upper surfaces when closed as high as the top of said shedding surface, and cross beams having upper shedding surfaces which do not extend higher than 50 the surface of the doors when closed.

3. In a dump car, the combination of a longitudinal sill structure having a shedding surface, dumping doors hinged thereto and having their upper surfaces when 55 closed as high as the top of said shedding

surface, and cross beams connected with the car sides and with said sill structure and having upper shedding surfaces which do not extend higher than the surface of the doors when closed.

70

4. In a dump car, the combination of a supporting member carrying a curved shedding surface, a dumping door adapted to cooperate with said surface, and, when closed, both the door and surface forming a portion of a horizontal floor, and, when open, both the door and surface forming a continuous inclined discharging device.

5. In a dump car, the combination with car sides of a floor having a longitudinal deflecting crown, cross deflecting crowns, and dumping doors adapted to be horizontal when closed, and having edges adjacent to said crowns, and having their upper surfaces substantially flush with the upper surfaces of such crowns, each door being hinged adjacent to one of said crowns and overlapping a portion of the same when the door is closed.

80

6. In a dump car, the combination with a longitudinal structure, of car sides, cross structures connecting the car sides and longitudinal structure, said longitudinal and cross structures all having upper shedding surfaces, and dumping doors adapted to be horizontal when closed, and having their upper surfaces substantially flush with the upper surface of such shedding members, and shields carried by the doors and moving over the adjacent shedding surface as the door drops.

90

7. The combination of a member having a curved upper surface, dumping doors on opposite sides of such member hinged on a common axis which is the center of curvature of such surface, and means at the inner edges of the doors substantially engaging such surface whether the doors be up or down.

100

8. The combination of a member having a curved upper surface, dumping doors on opposite sides of such member hinged on a common axis, which is the center of curvature of such surface, and shields carried by the doors and extending inwardly beyond their edges and adapted to engage such curved surface.

110

9. The combination of a supporting structure having a curved upper surface, a pair of dumping doors on opposite sides thereof, floor beams secured thereto, said floor beams extending inward beyond the edge of said doors and beneath said curved surface, and common hinge pins for opposite floor beams, said hinge pins being located at the center 120 of curvature of said curved surface.

120

10. The combination in a car, of a longitudinal sill, a cross structure comprising two channel beams extending over said sill and having their webs vertical, a channel beam 130

extending beneath said sill and having its flanges vertical, said flanges being secured to said webs.

11. The combination in a car, of a longitudinal sill structure extending at least from bolster to bolster, cross beams connected with the car sides and extending across such sill structure, a series of shedding crowns carried by the longitudinal structure between the cross beams, and dumping doors coöperating with such shedding crowns.

12. The combination in a car, of a longitudinal sill structure extending at least from bolster to bolster, cross beams connected with the car sides and extending across such sill structure, a series of shedding crowns carried by the longitudinal structure between the cross beams, dumping doors coöperating with such shedding crowns, said doors having floor beams extending inwardly beneath such crowns, means supported by the longitudinal sill structure for pivoting said beams, and shedding crowns carried by the cross beams adjacent to the ends of the doors, all of said crowns when the doors are closed not rising higher than the upper surface of the doors.

13. In a dump car, the combination of a plurality of dumping doors, a plurality of cables connected therewith, a cross head with which said cables connect, a guideway which carries said cross head allowing it to move, and a winding shaft connected with said cross head.

14. In a dump car, the combination of a cross head carrying rollers, stationary guides in which said rollers take, dumping doors, cables connecting the same with the cross head, and means for operating the cross head.

15. In a dump car, the combination with a plurality of dumping doors having adjacent ends, a bracket secured to the adjacent ends of two doors, a cable connected with said bracket, and means for operating said cable.

16. In a dump car, the combination of a series of dumping doors, and a series of raising cables, some of said cables being connected with two doors, and others being connected to a single door.

17. The combination with a car side having vertical stiffening members arranged in pairs, dumping doors and raising cables for the doors respectively located between the stiffening members of a pair.

18. The combination with dumping doors of raising cables suitably guided along the sides of the car, means for guiding said cables around the corner of the car, and means on the end of the car for drawing on said cables.

19. The combination with a car side having vertical stiffening members arranged in pairs, dumping doors, pulleys carried by the

sides of the car, between adjacent stiffening members, cables passing over said pulleys and downwardly to the doors, and mechanism for pulling on said cables.

20. In a dump car, the combination of a member the center of which is higher than the sides, a dumping door, and a shield carried by the door engaging the first mentioned member, whereby a substantially flat surface is formed when the door is closed.

21. In a dump car, the combination of a crown member and hinged dumping doors formed with means at their hinged edges for engagement with said crown and swinging about axes parallel therewith and adjacent thereto, whereby a substantially flat surface is formed when the doors are in closed position.

22. In a dumping car, the combination of a crown member and dumping doors having shields coöperating with said crown member, whereby when said doors are opened there are formed two surfaces sloping in opposite directions the planes of the surfaces intersecting substantially in the center plane of the crown member.

23. In a dump car, the combination of a crown member, the center of whose surface is higher than its sides, a dumping door having a shield adapted to coöperate with said surface, and when closed, the door shield and surface forming a portion of a horizontal floor, and when opened, the door shield and surface forming an inclined discharge surface.

24. In a dump car, the combination of a crown member the center of which is higher than the sides, a dumping door, and means carried by the door to engage the upper surface of the crown member to make a tight joint.

25. In a dump car, the combination of a crown member the center of which is higher than its sides, a dumping door and shields carried by the door and adapted to overlap the upper surface of said members to make a tight joint when the doors are closed.

26. In a dump car, the combination of a stationary member having a curved upper surface, a pair of doors movably mounted with edges adjacent to such surface, and means for preventing leakage between said doors and surface, said means being secured to the doors and bearing on said surface.

27. A dump car having in its floor dumping doors and stationary members arranged to present a substantially flat surface when the doors are closed, and an inclined shedding surface throughout when the doors are dropped, and means for insuring tight joints to the edges of the doors when closed.

28. In a dump car, the combination of a stationary member having a curved upper surface, a hinged dumping door, and a member at the inner edge of the door having a

curved under surface coöperating with the curved upper surface of said stationary member.

29. In a dump car, the combination of a stationary member having a curved upper surface, a hinged dumping door, a shield carried by said door and adapted to engage said surface, and a filling member beneath the shield to make a tight joint.

10 30. In a dump car, the combination of a longitudinal crown, hinged dumping doors having their upper surfaces when closed as high as the top of said crown, and means carried by the door to engage the curved 15 surface of the crown to make a tight joint.

31. In a dump car, the combination of a longitudinal member, a door hinged thereto, transverse members between which said door may swing, and shields projecting from the

20 ends of the door and adapted to abut beneath said transverse members when the door is brought into closed position.

32. In a dump car, the combination of a dumping door composed of tongue and 25 groove planking, and shields carried by the door and extending across the ends thereof transversely of the seams between the planks.

33. In a dump car, the combination of a 30 dumping door composed of tongue and groove planking, and shields carried by the door and extending across the ends thereof, transversely of the seams between the planks, said shields being bent at an angle to also 35 project from the ends of the door, and cross members with which such projecting portions coöperate.

34. In a dump car, the combination of a 40 shedding crown and a pair of doors hinged on a common axis below said crown and having their inner edges formed to overlap the top of the crown when the doors are closed.

35. In a dump car, the combination of a 45 pair of doors hinged at the longitudinal center of the car, a longitudinal center sill carrying such hinge, and a stationary member having a shedding surface carried by the sill above such hinge, said doors being provided with means adjacent to their hinged

edges to overlap the top of said shedding surface.

36. In a dump car, the combination of a shedding surface and a dumping door supported on an axis below said surface and 55 having means overlapping the top of the surface when the door is closed.

37. In a dump car, the combination of a stationary shedding surface and a dumping door hinged on an axis below said surface 60 and having its edge overlapping the top of said surface when the door is closed.

38. In a dump car, the combination of a shedding member, and a door adapted to be horizontal when closed and when closed 65 having its upper surface as high as the top of the shedding member, said door being provided with means at its edge to overlap said top.

39. In a dump car, the combination of a 70 shedding member, a door adapted to be horizontal when closed and when closed having its upper surface as high as the top of the shedding member, said door being provided with means at its edge to overlap 75 said top, and means below said top for supporting said door on an axis.

40. In a car, the combination of a member having a rounded top and a dumping door having a top surface adapted to be 80 substantially tangent to the curve of the top whether the door be up or down.

41. In a car, the combination of a longitudinal rounded-top member and a transverse rounded-top member, and a dumping 85 door whose surface when closed is in a plane substantially tangent to both members.

42. In a car, the combination of a longitudinal central beam having a rounded top and transverse members extending inwardly 90 from the sides of the car and rounded at their tops, and dumping doors the top surfaces of which when closed are as high as said tops.

In testimony whereof, I hereunto affix my 95 signature in the presence of two witnesses.

FRANK S. INGOLDSBY.
